AMMUNITION

Alfons G. Schuricht, Alton, and Albert J. Hinrichs, East Alton, Ill., assignors to Western Cartridge Company, East Alton, Ill., a corporation of Delaware

Application November 29, 1935, Serial No. 52,136

13 Claims. (Cl. 102—15)

This invention relates generally to the manufacture of shot shells and particularly to a novel base wad and the shot shell embodying the same as well as the process of making such base wads.

5 In the manufacture of shot shells, as heretofore practiced, it has been customary to provide a paper tube, one end of which is closed by a suitable metallic head and on the interior of the metallic head a base wad is provided. Such 10 base wad ends perform the function of securing the paper tube in position within the metallic head and holding the battery cup in position therein and to an extent, of sealing the headed end of the shot shell against gas leakage. In 15 accordance with the usual practice such base wads have been formed in situ, that is to say, after a slug or cylinder of base wad material has been placed in position in the shot shell the pressure of a plunger is exerted upon the 20 slug or cylinder so as to conform the same and cause it to flow into the flange of the head and around the battery cup so as to securely hold these parts together. Ordinarily the shell is headed, that is to say, finally flanged and formed 25 at the same time the base wad is formed.

The object of the present invention, generally stated, is to provide a shot shell in which the base wad is largely preformed.

Another object of this invention is to provide 30 an improved base wad for shot shells and particularly one which has been radially compressed and condensed.

A further object of this invention is to provide 35 a process of making base wads and shot shells wherein the resulting structure will be of superior strength and more securely sealed against gas leakage than has been heretofore possible.

A more specific object of this invention is to provide 40 a shot shell base wad in which the wad largely preformed before insertion into the shot shell tube but thereafter is finally formed so as to secure the parts together.

Other objects will become apparent to those 45 skilled in the art when the following description is read in connection with the accompanying drawing, in which:

Figure 1 is a perspective view of a base wad blank suitable for use in accordance with the present invention;

Figure 9 is a detail view of an overlay for use with the base wad of Figure 8.

Figure 10 is a detail view showing the associated relation of the base wad of Figure 8 and the overlay of Figure 9. 15

Figure 11 is a sectional view showing a shot shell having the assembly of Figure 10 in position therein but not finally formed.

Figure 12 is a similar sectional view showing the assembly of Figure 11 after final formation. 20

In accordance with the present invention, generally stated, the base wad of a shot shell may be substantially preformed before it is inserted into the shot shell. By substantially "preformed", as used herein, is meant that the base 25 wad previous to insertion in the shot shell has been compressed and condensed to the desired extent except for certain parts which are left free to be further condensed in situ in order to secure the parts of the shot shell together. The present invention contemplates that the preformed base wad be so treated that it is condensed and compressed radially as well as axially so that before insertion into the shot shell the base wad, as to some of its faces, is finally 30 formed, and after insertion into the shot shell further deformation of the wad is accomplished 35 merely to secure the parts together. In practice the radial compression may be accomplished in one or more stages as by forcing the blank 40 through a series of tapered dies.

In accordance with one embodiment of the present invention the preformed base wad may be provided with projecting parts in the region adjacent the other parts of the shot shell which it is desired to secure together. In accordance 45 with one embodiment such projections may be left in the region of the shot shell head and battery cup so that upon axial compression after being inserted in the shot shell tube the projecting parts flow into the flange of the head and other adjacent parts so as to securely anchor the various parts together. In accordance with another embodiment, however, projections may also be 50 left upon that end face of the base wad which will be adjacent the propellant charge. The latter arrangement is particularly adaptable for use in connection with overlays so that the projection 55 may extend through an aperture in the overlay. 60

lay and upon final compression be peened over so as to secure the overlay in position.

Referring now particularly to the drawing, in Figure 1 there is illustrated a base wad blank 1 which, in the embodiment shown, is formed of convolutions of paper in accordance with the usual practice. As shown the base wad blank 1 is in the form of a cylinder and in the condition illustrated in Figure 1 is of slightly larger diameter 10 than the shot shell in which it is to be employed. Although in the embodiment illustrated the blank 1 is formed of convolutions of paper, it will be understood that it may be formed of other plastic material, as for instance cellulose, wood fibre 15 or bagasse.

In accordance with the present invention the blank 1 may be compressed both axially and radially. This may be accomplished by forcing the blank through suitable reducing dies, such as 2, 20 by means of a plunger 3 so as to reduce the diameter thereof, down to approximately the same diameter as the interior of the shot shell tube in which it is to be employed. If a modified conventional form of shot shell heading apparatus 25 is employed, the compressed blank 1 may be discharged from reducing die 2 into a carrier plate suitably mounted so as to carry the wads and other shell parts through the successive forming operations. Such a carrier plate may be provided 30 with a series of openings, such as 4, to receive compressed blanks from die 2 and carry them to the next succeeding operation. After thus compressing and condensing the blank 1 it may be subjected to a further pressing operation 35 in order to conform it to the extent desired. This may be accomplished, as shown in Figure 3, by the action of cooperating plungers 5 and 6, one of which (in this case, the latter) is so shaped as to form the desired chamber. In the apparatus illustrated in Figures 2 and 3 the plungers 3 and 5 are provided with tenons 7 arranged to pass into the central aperture of the base wad blank 1 and thus prevent closing of that aperture. The end of plunger 6 may be provided 45 with an opening to receive tenon 7 when the plungers are moved together. It is apparent, therefore, that when the plungers 5 and 6 are brought together with the previously condensed base wad blank 1 therebetween, the same will be compressed and conformed to the shape of the plunger so as to produce a preformed base wad, such as that illustrated in Figure 4.

In the embodiment shown in Figure 4 the pre-formed base wad is provided at its outer end face 55 with a suitably shaped powder chamber 8 corresponding in shape to the end of plunger 6, whereas on its inner end projections which, in the embodiment illustrated are in the form of annular lips 9 and 90, are left so as to be finally 60 conformed within the shot shell head. In order to facilitate flowing of the wad material into the flange of the metallic head and about the battery cup, lips 9 and 90 may be tapered. For instance, lip 9 may be tapered inwardly and lip 90 outwardly.

In the condition illustrated in Figure 4, the pre-formed base wad is inserted into a shot shell tube 10 upon which is assembled a semi-formed metallic head 11 carrying a battery cup 12. After 70 such assembly pressure is exerted upon the interior of the shot shell tube so as to force the pre-formed base wad down into the head and around the battery cup 12. This may be accomplished by a suitable plunger such as 13. At the same 75 time by the action of the conventional bunter

the head may be finally flanged. During this operation it will be understood that the shot shell tube 10 and the head 11 are supported so as to prevent rupture.

The pressure exerted by the plunger 13 causes 5 projections 9 to flow into the flange of head 11 and around battery cup 12 so as to anchor these parts together and to produce a strong structure, as shown in Figure 6, where it will be observed that the base wad has been so compressed that 10 projections 9 and 90 have practically flowed together.

After the shot shell is thus headed it may be loaded with a suitable propellant charge 14 upon which is placed wadding 15 and thereabove a 15 charge of shot 16 and the shell is finally closed by a further wad 17 crimped in position.

In accordance with another feature of the present invention a plastic overlay is provided in conjunction with and secured to a base wad. 20 In accordance with an illustrative embodiment the base wad may be formed to the desired shape, as for instance that illustrated in Figure 8, either within or without the shell so as to have a projection at one face. For example, a blank may 25 be condensed, as hereinbefore described, and the wad preformed so as to provide a body portion 18 and a projecting portion 19 on the end face thereof which is to be adjacent the propellant charge. For facilitating the flowing of the base 30 wad material into the flange of metallic head the flange may also be formed with an annular lip 24, tapered on the inside as shown at 25 so that upon compression in the shell the lip will turn out into the flange and secure the parts together. It will 35 be understood, however, that the plastic overlay may, according to this invention, be secured to a base wad which has been formed by molding, or preformed by axial compression only, or formed in situ in the shell so as to leave a projection 40 on the outer face for connection with the overlay.

Over the projection, such as 19, may be placed an overlay disc 20. The overlay disc 20 may be formed of suitable plastic material, such as 45 heavy paper, and provided with a central aperture, such as 21, formed to fit over projection 19. This assembly may then be forced through a suitable die in order to cup the plastic overlay and provide flanges 22 thereon. It may be pointed 50 out, however, that this operation may be accomplished as the base wad is moving into a shell tube as by the provision of a suitable die above the mouth of the shell into which the assembly is being moved or by cupping the disc 20 separately. In the operation of thus cupping the plastic overlay a suitable plunger is employed, the diameter of which is sufficiently less than the interior diameter of the shot shell tube that the edges of the overlay disc 20 may be accommodated but the plunger may advantageously be of as great a diameter as possible in order to cause 55 the flanges 22 to snugly engage the interior walls of the shot shell tube, as shown in Figure 11.

With the base wad and overlay thus inserted 60 in the shot shell tube the shell may be finally headed and at the same time the projection 19 may be peened over on the outside of overlay 20, as shown at 23, in order to securely hold the overlay in position within the tube. In the last mentioned heading operation it will, of course, be understood that sufficient axial compression is applied to the structure that the base wad is forced into close engagement with the interior of the head and around the battery cup, and the lip 70 75

24 is turned out into the flange of the metal head so as to securely anchor all these parts together with the overlay.

From the foregoing description it will be apparent that the present invention provides a pre-formed base wad and a shot shell employing the same in which a structure of superior strength in the head region is accomplished. By thus preforming the base wad the wad may be condensed axially so as to substantially reduce the liability of gas leakage through the head without, at the same time, rendering the shot shell tube and head liable to rupture because of excessive pressure applied thereon. Thus while in the manufacture of shot shells in accordance with the conventional practice there is a practical limit to the pressure which may be applied when the base wad is conformed in situ due to the liability of the head and tube to rupture, this is overcome by subjecting the wad to radial compression without the shell. The provision of the plastic overlay on the other hand, constitutes a further means for overcoming the liability of gas leakage through the wad and when used in conjunction with a preformed base wad, such as that described hereinbefore, the resultant shot shell may be made sufficiently strong by applying a high degree of pressure during the preforming operation that it is unnecessary to employ the usual steel reenforce within the head.

From the foregoing description it will be apparent that many modifications of the base wad, shot shell and process hereinbefore described will present themselves to those skilled in the art without departing from the spirit of this invention. It is to be understood, therefore, that the foregoing description of two embodiments and the drawing in support of the same are merely illustrative of the process and the adaptability thereof in the conventional process of making shot shells and it is not to be understood that the invention is limited to these specific embodiments. It is to be distinctly understood, therefore, that such modifications and the use of such individual features and sub-combinations of features as do not depart from the spirit of this invention are, although not specifically described herein, contemplated by and within the scope of the appended claims.

Having thus described the invention, what is claimed is:

1. In the art of making shot shells the process comprising, forming and condensing a base wad approximately to shape but with a projection on the end face, placing an overlay on said wad with said projection extending through a hole in said overlay, inserting the overlay and wad in a shell tube, and compressing the assembly to peen the projection over on the outer side of the overlay.

2. In the art of making shot shells the process comprising, forming and condensing a base wad approximately to shape but with a projection on the outer end face, providing a flat plastic disc of substantially larger diameter than the tube of the shell and having a central hole, placing the disc over the preformed base wad with said projection extending through the hole, inserting the assembly in a shot shell tube with the disc cupped to form flanges extending along the walls of the tube, and applying pressure to the assembly interiorly of the flanges to seat the wad and disc in the shell.

3. A shot shell having a base wad, and an overlay secured to and interlocked with the base wad.

4. A shot shell having a base wad, and an overlay for the base wad, said base wad having a projection extending through a hole in said overlay.

5. A shot shell having a base wad, and an overlay for the base wad, said base wad having a projection extending through a hole in said overlay and peened thereover.

6. In the art of making a shot shell, having a base provided with a rim and an inwardly projecting primer cup therein, the process comprising, preforming a base wad blank composed of convolutions of paper surrounding a perforation, by condensing the blank while sustained externally to fit the base and internally to fit the cup, inserting the preformed blank into the base and over the cup and securing the inserted blank in the base.

7. In the art of making a shot shell having a base provided with a rim and an inwardly projecting primer cup, the process comprising, preforming a base wad blank to provide a distinct circumferential flange projecting from its base end, inserting the preformed blank into the base over the cup and interlocking the flange of the blank with the rim of the base.

8. In the art of making a shot shell, having a base provided with a rim and an inwardly projecting primer cup therein, the process comprising, preforming a base wad blank composed of convolutions of paper surrounding a perforation to provide a distinct circumferential flange projecting from its base end, inserting the preformed blank into the base over the cup and interlocking the flange of the blank with the rim of the base.

9. In a shot shell having a base provided with a rim and an inwardly projecting primer cup therein, a preformed base wad composed of convolutions of paper surrounding a perforation and having a distinct circumferential flange projecting from its base end, said wad being condensed and sized externally to fit the base and internally to fit the cup, and said flange being adapted to interlock with the rim of the base.

10. In a shot shell having a base and an inwardly projecting primer cup therein, a preformed base wad composed of convolutions of paper surrounding a perforation and condensed and sized externally to fit the base and internally to fit the cup.

11. A shot shell having a base and an inwardly projecting cup therein, a preformed base wad composed of convolutions of paper surrounding a perforation and having a distinct circumferential flange projecting from its base end, said base wad being condensed and sized externally to fit the base and internally to fit the cup.

12. In the art of making a shot shell having a base wad, the process comprising, inserting an overlay into the shell and onto the base wad and operating on the overlay to interlock it with the base wad.

13. A shot shell having a base wad, and a cuffed overlay for the base wad, said overlay having a flange engaging the shell, and means on the base wad for interlocking said overlay therewith.
